Primary Examiner — Daniel D Bui*Assistant Examiner* — Andrew Kerr(74) *Attorney, Agent, or Firm* — Bond, Schoeneck & King, PLLC(57) **CLAIM**

The ornamental design for a cup, as shown and described.

DESCRIPTION

FIG. 1 is a perspective view of a cup showing our new design;

FIG. 2 is a reverse side view of the cup shown in FIG. 1; FIG. 3 is a front side view of the cup shown in FIG. 1; FIG. 4 is a left side view of the cup shown in FIG. 1; FIG. 5 is a right side view of the cup shown in FIG. 1; FIG. 6 is a top view of the cup shown in FIG. 1; and, FIG. 7 is a bottom view of the cup shown in FIG. 1.

The broken lines in the drawing views represent unclaimed portions of a cup, which are included for the purpose of illustrating unclaimed environment only, and forms no part of the claimed design.
